UNITED STATES PATENT OFFICE.

CHARLES MEHLIN, OF FORT LEE, NEW JERSEY.

PIANO CONSTRUCTION.

Application filed August 3, 1922. Serial No. 655,421.

This invention relates in general to piano construction, and has for its object broadly the provision of a sound board construction and arrangement of increased strength and durability and improved tone quality.

In the usual piano construction, prior to my invention, the sound board of the piano is curved or crowned slightly and has been reinforced by reinforcing ribs weakened at their ends to reduce the stiffness. My present invention contemplates, from one of its aspects, the production of a full tone quality without thus weakening the ribs, thereby providing a much more sturdy construction.

Another important object of the invention results from the discovery that the interruption of any of the fibres of the ribs directly affects the pitch produced by vibration of the parts and from this aspect the invention contemplates the provision of ribs, the fibres of which will be uninterrupted throughout the length of the rib.

In the past it has been generally the custom to secure the bridge by dowels passing through the ribs to provide secure bottom or back anchorage, and I have found that better musical results are obtained if separate anchorage is provided for these fastening dowels.

The present invention comprises a number of features interrelated in the production of certain desirable results and which, however, have separate value when used alone and it is my intention to claim and protect the invention in its several aspects.

Numerous other objects and advantages of the invention will be apparent as it is better understood from the following description, which, taken in connection with the accompanying drawings, discloses a preferred embodiment thereof.

Referring to the drawing,

Figure 1 is a view of so much of a piano as is necessary to an understanding of the invention;

Fig. 2 is a section taken substantially on the line 2-2 of Fig. 1;

Fig. 3 is a section taken across the sound board adjacent one of the ribs; and

Fig. 4 is a section showing the sound board mounting and the bridge fastening.

For the purpose of illustrating my present invention, I have shown on the drawing a portion of a grand piano, although it will

be understood that the invention can be as readily employed in an upright. Reference character 11 indicates the outer rim extending about the piano in the usual fashion, reference character 12 the inner rim, reference character 13 the sound board, reference character 14 the rail, and reference character 15 the cross block.

The sound board is arranged with its fibres extending from the lower right hand corner of Fig. 1 diagonally up to the upper left hand corner and it will be understood that the only difference between an upright and a grand piano is that in the one the sound board is arranged vertically and the other horizontally. The sound board is secured upon the inner rim 12 about three sides of the piano and to the block 15 at the fourth side. The sound board is preferably cut away at 16 to provide a free edge 17 at right angles to the direction of the fibres of the sound board and across the longest dimension thereof. This is the construction of my earlier Patent #1,335,791 and this feature possesses the advantages therein described. The sound board is reinforced by a plurality of ribs 18 arranged also at right angles to the fibres and extending across the sound board. The sound board is crowned, as shown in Fig. 3 and the ribs are of full thickness or height throughout their length. That is to say, they are not cut away at the ends as has been usual in the past. In the present instance they are built up or constructed of two parts, namely a lower rectangular member 19 and an upper member 21 accommodating the crown of the sound board. The line or plane of joint 22 is so arranged that it terminates at its ends within the ends of the sound board.

Thus constructed the ends of the ribs 19 are mortised in throughout the full thickness thereof into the rim 12 and the block 15, thus providing a structure of strength much greater than has heretofore been usual. As has been earlier stated, I have discovered that the pitch resulting from vibration of the ribs (which are connected to the sound board) is directly affected by the interruption of the rib fibre. In the past it has been usual to support the bridges (indicated by reference characters 24 and 25) by dowels, which have extended through the ribs, the sound board and into the bridges. I overcome this objection by arranging dowel re-

ceiving blocks 26 on behind the sound board to take the dowels 27 extending into the bridges 24 and 25.

The full depth ribs can, of course, be employed without providing the free edge 17 in the sound board and I have discovered that where this free edge is provided the ribs may be stiffer than where it is omitted since this free edge adds greatly to the freedom of vibration of the sound board and compensates therefore for restriction placed upon sound board vibration by stiffening of rib construction.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a piano, the combination of a curved sound board, and ribs stiffening the same, said ribs being of full thickness throughout their length and the height thereof being varied in accordance with the contour of the sound board.

2. In a piano, the combination of a crowned sound board, and ribs stiffening the same, said ribs being of uniform width and varying from even thickness throughout their length substantially only by the amount of crowning of the sound board.

3. In a piano, the combination of a rim, a sound board secured at three sides to said

rim, a rail supporting said sound board at the fourth side, and ribs reinforcing said sound board and engaged in said rail and said rim and of full thickness throughout their length.

4. In a piano, the combination of a rim, a sound board secured at three sides to said rim, a rail supporting said sound board at the fourth side, and ribs reinforcing said sound board and engaged in said rail and said rim and of full thickness throughout their length, said sound board being cut 50 away to provide a free edge at right angles to the grain thereof.

5. In a piano, the combination of a sound board, bracing ribs, and bridge members secured to said sound board on opposite sides, the fibres of said bracing ribs being uninterrupted and the bridge secured to said sound board intermediate said bracing ribs.

6. In a piano, the combination of a sound board, bracing ribs, and bridge members secured to said sound board on opposite sides, the fibres of said bracing ribs being uninterrupted and the bridge secured to said sound board intermediate said bracing ribs and dowel holding members arranged between 65 the ribs.

7. In a piano, the combination of a sound board, a plurality of bracing ribs, and bridge members secured to said sound board, said bridge members being secured to the sound board intermediate the bracing ribs by dowel blocks arranged on the opposite side of the sound board, and dowel members passing through said blocks, said sound board and into said bridge.

CHARLES MEHLIN
